UNITED STATES PATENT OFFICE.

BENJAMIN L. MACK, OF ESSEX, CONNECTICUT.

IMPROVEMENT IN STOP-MOTIONS FOR KNITTING-MACHINES.

Specification forming part of Letters Patent No. 42,672, dated May 10, 1864.

To all whom it may concern:

Be it known that I, BENJAMIN L. MACK, of Essex, in the county of Middlesex and State of Connecticut, have invented a new and Improved Stop-Motion for Knitting-Machines; and I do hereby declare that the following is a full, clear, and exact description of the same, reference being had to the accompanying drawings, forming part of this specification, in which—

Figure 1 is a front view of the stop motion. Fig. 2 is a plan of the same.

Similar letters of reference indicate corresponding parts in both figures.

This invention consists in the arrangement of a locking device in combination with the belt-shipper, whereby the yarn in passing from the bobbin to the conductor of the machine is caused to hold up the said lever, and makes it lock the shipper in condition to keep the machine running; but when the yarn gives out or breaks, the said lever, being no longer held up, is acted upon by gravitation in such manner as to unlock the shipper and allow the machine to be put out of gear by the spring or its equivalent provided for the purpose.

To enable others skilled in the art to make and use my invention, I will proceed to describe its construction and operation.

A is a horizontal plate, intended to be bolted to the bed plate or frame of the knitting-machine. This plate has cast with or firmly secured to it a small upright standard, B, and two bearings, a a, to receive the horizontal sliding rod C, which carries the belt-shipper D. The rod C has applied to it a spring, b, which always tends to push it in a direction to keep the belt on the loose pulley or to ship it from the fast to the loose one. One end of the rod C is connected with the lower end of a short lever, E, which works on a fixed fulcrum-pin, c, secured in the lower part of the standard B. This lever is slotted longitudinally, as shown at d in Fig. 1, where the fulcrum passes through it to allow the lever to slide on the pin far enough to permit the rod C to have a rectilinear motion. The upper

end of the said lever is formed with an arc, e, in the edge of which there is a notch, f.

F is the locking lever, which constitutes the principal feature of my invention, arranged to work on a fixed fulcrum secured in the upper part of the standard B. This lever has a longer and a shorter arm, and the end of the shorter arm is turned down to form a tooth, h, to enter the notch f of the lever E, for the purpose of locking the said lever in the position shown in black outline in Fig. 1, in which position it keeps the shipper opposite to the fast pulley and the belt on that pulley. The end of the longer arm of the said locking-lever is made with an inverted hook or crook, i, to serve as a guide for the yarn j on its way from the bobbin to the conductor of the machine.

On the top of the standard B there is a fixed guide, G, over which the yarn passes. The excess of weight of the longer arm of the lever F over that of the shorter arm is supported by the yarn between the bobbin and the guide B, so long as any yarn remains on the bobbin and while it is unbroken between the bobbin and the needles. When the yarn breaks or gives out, and so ceases to support the longer and heavier arm of the locking-lever F, the said arm drops, as shown in red outlines in Fig. 1, and raises the tooth h out of the notch f, thereby unlocking the lever E and leaving the rod C under the influence of the spring b, which moves it and the attached belt-shipper to a position to throw the machine out of gear.

What I claim as my invention, and desire to secure by Letters Patent, is—

The locking-lever F, having a heavier arm to be supported by the yarn and a lighter-toothed arm, in combination with a notched lever, E, connected with a spring shipper, all substantially as and for the purpose herein described.

BENJAMIN L. MACK.
